COOLED X-RAY TUBE HEAD

Edwin R. Goldfield, University Heights, and Edward B. Graves, South Euclid, Ohio, assignors to Picker X-Ray Corporation, Waite Manufacturing Division, Inc., Cleveland, Ohio, a corporation of Ohio

Application February 23, 1942, Serial No. 431,922

7 Claims. (Cl. 250—89)

This invention relates to improvements in the cooling of X-ray tube heads and provides means whereby X-ray tubes may be used continuously for long periods of time.

One of the objects of the present invention is to provide a very compact tube head with the cooling apparatus built into the tube housing structure so that the entire equipment occupies very small space and yet provides a very efficient cooling system.

Another object of the present invention is to combine an X-ray tube and its associated transformer equipment in a single compact cooling system.

Other objects and advantages include the detailed arrangement of the air blowing means and partition means in the housing, the formation of the housing cover to provide part of the cooling system, and the provision of novel means for supporting the entire tube head and housing. All of these will be apparent from the accompanying drawings and description and the essential features will be set forth in the claims.

In the drawings, Fig. 1 is an end elevational view of our improved tube head; Fig. 2 is a side elevation thereof; Fig. 3 is a transverse sectional view taken approximately on the line 3—3 of Fig. 4; Fig. 4 is a view partly in end elevation and partly in section taken along the line 4—4 of Fig. 2; Fig. 5 is a top plan view of an interior casing taken along the line 5—5 of Fig. 4; while Fig. 6 is a fragmental sectional view taken approximately along the line 6—6 of Fig. 3.

One of the problems encountered in continuous operation of X-ray tubes is the dissipation of heat both from the tube and the transformer. Heretofore cumbersome equipment has been utilized to dissipate this heat but our present invention provides a very efficient means for this purpose concentrated in such a small space that the equipment may be used where great portability is desired, such as, for instance, the use of X-ray equipment with an army in the field.

Referring to Fig. 4, an inside liquid-tight casing 10 is provided extending from end to end of the head. This casing has a removable cover 11 attached by securing members 12 and provided with suitable gasket means so that no liquid can escape from the casing. Within the casing is mounted an X-ray tube 13 and a transformer 14 of a usual type provided with taps for filament current, and other taps for tube current in the usual well known manner. Such connections need no illustration here. The casing 10 is filled with a heat conducting electrical insu-

lating liquid, such as one of the oils commonly used for this purpose. Within the casing and submerged in the oil thereof is an impeller 15 driven by a motor 16. This impeller 15 is preferably approximately opposite the target of the tube but not necessarily so. When the tube and transformer are in operation, the motor 16 is running and the impeller 15 keeps the oil in the casing 10 in circulation. This transfers heat from the tube and the transformer to the walls of the casing 10. These walls are of a heat conducting material and readily dissipate the heat to the outer surface of the casing. Means is provided as hereinafter disclosed for causing a stream of air to pass continuously over the outer surface of the casing 10 so as to carry away the heat from that point.

Communicating with the interior of the casing 10 are expansion bellows housed in the projections 17 and 18. These are of the usual type to take care of expansion and contraction of the liquid in the casing 10 under varying heat conditions. One of these bellows may be equipped with a safety switch for preventing overheating 25 of the tube such as is disclosed in the copending application of Edwin R. Goldfield, Serial No. 358,602, filed September 27, 1940.

An outer housing 19 has side walls as best seen in Fig. 4, generally parallel to and spaced 30 from the side walls of the casing 10, thus providing air passageways along both sides of the casing. The housing has a perforated semicylindrical bottom wall 19a. The housing is completed by the end walls 19b which are imperforate except for openings 19c, the purpose of which will later appear. The side walls of the housing are cut away as shown at 19d, Fig. 2, so that the projections 17 and 18 may enter into the cut-away portion of the housing, after which 35 plates 20 on each side are secured in place by screws 21, thus fixing the position of the housing 19 outside of the casing 10. A removable cover 22 is provided for the housing 19 overlapping the side walls thereof at 22a when the cover is in place. There is thus provided a continuous passageway for air up the left-hand side of casing 10 as viewed in Fig. 4, across the top thereof through the cover 22 and down the right-hand side as indicated by the arrows. The cover 22 40 provides access to the top cover of the casing 10 which is shown at 11 in Fig. 5. This top cover carries the binding posts for the connections leading to the various electrical equipment within the casing 10. The binding posts 23 are 45 for the motor 16. The binding posts 24 lead

to the safety switch previously referred to as housed in one of the projections 17 or 18. The binding posts 25 are for the filament transformer, and the binding posts 26 are for the main transformer connections. The opening 10b is for the emission of X-rays and is closed by a plastic window.

Mounted in the cover 22 are the diaphragm shutters 27 for controlling the X-rays from the tube 13. The position of the shutters is controlled by the rod 28 which extends through a suitable opening in the cover. Further description of these shutter diaphragms is unnecessary as they are similar to those disclosed in the copending application of Goldfield, Schiring and Stava, Serial No. 386,390, filed April 2, 1941. This shutter equipment is affixed to the bosses 29 in the cover.

When in use, the usual cone sets in the depression 22b and the opening in the top of the cover is closed sufficiently airtight by an aluminum filter 22c about $\frac{1}{4}$ mm. thick or by a plastic sheet of equivalent X-ray filtration.

Means for circulating the air is provided within the housing 19 and closely adjacent to one wall of the casing 10 so as to provide a very compact equipment. As here shown this blower means is beneath the casing 10 and within the semicylindrical portion 19a of the housing, thus giving a very pleasing appearance to the complete head. A motor 30 is suitably supported in the mid portion of the housing and has its drive shaft 30a extending toward each end of the housing. Mounted on each shaft is an impeller 31 preferably having a double set of blades separated by the partition 31a. Around the impeller is the usual involute housing 32 which lies against the inner face of the housing at 32a, thus closing off the perforations in the bottom of the housing and giving a closed conduit for air up to the point 32b where the air is discharged from the blower into the passageway between the casing 10 and the housing 19. Thus air will enter at the center of the impellers 31 and be discharged at 32b to follow the arrows around three sides of the casing 10 and being discharged through the perforations 19c at the outlet side of the housing. To insure that warm air at the outlet is not drawn into the impellers, a partition plate 33 extends between the impeller housings 32 at the right-hand side of the motor 30 as seen in Figs. 3 and 4. Air enters the impellers 31 through the openings 19c in the ends of the housing 19. Air may also enter at the annular openings 32c around the shafts 30a. Because of the partition 33 this inlet air must come through the perforations 19f at the left-hand side of the housing 19 as viewed in Figs. 3 and 4.

The tube head may be supported from a suitable tube stand in any desired manner but as here shown supporting arms 34 are indicated engaging the projections 17 and 18.

It will thus be seen that we have provided a very compact and efficient cooling means for an X-ray tube and transformer, all contained within a single housing of very pleasing appearance and occupying very little space. This equipment therefore is easily carried with an army in the field and can be operated for long periods continuously without danger of overheating the tube or the transformer. The overall dimensions of the head inside the Sylphon housings 17 and 18 are 7½ inches wide, 10½ inches long and 13½ inches high.

What we claim is:

1. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower means positioned in said housing and below said casing, and partition means for causing a stream of air from said blower means to traverse said passageway up one side of said casing, across the top thereof and down the other side of said casing.

15 2. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower means positioned in said housing and below said casing and including a rotatable impeller and a rounded casing therefor, said housing having a bottom wall merging with and generally following said rounded impeller casing, and partition means for causing a stream of air from said blower means to traverse said passageway up one side of said first named casing, across the top thereof and down the other side of said first named casing.

25 3. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower means positioned in said housing and below said casing and including a rotatable impeller and a rounded casing therefor, said housing having a perforate bottom wall merging with and generally following said rounded impeller casing, and partition means for causing a stream of air impelled by said blower means to enter said perforate bottom wall at one side thereof, to traverse said passageway up one side of said first named casing, across the top thereof, down the other side of said first named casing and out of said perforate bottom wall at the other side thereof.

40 4. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower means positioned in said housing and below said casing and including two rotatable impellers and a motor between them having driving connections with them, each impeller having a rounded casing, said housing having a perforate bottom wall merging with and generally following said rounded impeller casing, and partition means for causing a stream of air impelled by said blower means to enter said bottom wall and pass around said casing in said passageway and thence pass out through said bottom wall.

45 5. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower

means positioned in said housing and below said casing and including two rotatable impellers and a motor between them having a driving shaft connected with them, each impeller having a casing arranged to discharge air upwardly along one side of said first named casing, said housing having a perforate bottom wall in the central zone opposite said motor, there being openings through each impeller casing positioned axially of the impeller and on opposite sides thereof, and partition means in said central zone of the bottom portion of said housing between said impeller casings, whereby air from one side of the bottom portion of said housing enters centrally of each impeller at opposite sides thereof and then passes around three sides of said first named casing and out at the other side of the bottom portion of said housing.

6. An X-ray tube head comprising a liquid-tight casing of heat conducting material, an X-ray tube in said casing, heat conducting electrical insulating oil in said casing surrounding said tube, means for agitating said oil, a housing spaced from the outside of said casing and providing a passageway around said casing, blower means positioned adjacent said passageway for causing a flow of air therethrough, said housing including a cover adjacent said casing cover and removable for access to said casing, there being aligned X-ray pervious partitions in said casing and housing covers for passage of X-rays, and said covers when in place providing walls of said passageway.

causing a flow of air therethrough, said housing including a cover removable for access to said casing, said casing carrying electrical connections for said tube accessible upon removal of said cover, and said cover when in place providing a wall of said passageway.

7. An X-ray tube head comprising a liquid-tight casing of heat conducting material, an X-ray tube in said casing, a cover for said casing providing access to the interior thereof, heat conducting electrical insulating oil in said casing surrounding said tube, means for agitating said oil, a housing spaced from the outside of said casing and providing a passageway around said casing, blower means positioned adjacent said passageway for causing a flow of air therethrough, said housing including a cover adjacent said casing cover and removable for access to said casing, there being aligned X-ray pervious partitions in said casing and housing covers for passage of X-rays, and said covers when in place providing walls of said passageway.
